(57) **CLAIM**

The ornamental design for display screen or portion thereof having a graphical user interface for displaying an animated wait icon, as shown and described.

DESCRIPTION

FIG. 1 is a front view of a first embodiment of a display screen or portion thereof having a graphical user interface for displaying an animated wait icon showing my new design;

FIG. 2 is a front view of a second image thereof;
FIG. 3 is a front view of a third image thereof;
FIG. 4 is a front view of a fourth image thereof;
FIG. 5 is a front view of a fifth image thereof;
FIG. 6 is a front view of a sixth image thereof;
FIG. 7 is a front view of a seventh image thereof;
FIG. 8 is a front view of a eighth image thereof;
FIG. 9 is a front view of a ninth image thereof;
FIG. 10 is a front view of a tenth image thereof;
FIG. 11 is a front view of a eleventh image thereof;
FIG. 12 is a front view of a twelfth image thereof;
FIG. 13 is a front view of a thirteenth image thereof;
FIG. 14 is a front view of a second embodiment of a display screen or portion thereof having a graphical user interface for displaying an animated wait icon showing my new design;

FIG. 15 is a front view of a second image thereof;
FIG. 16 is a front view of a third image thereof;
FIG. 17 is a front view of a fourth image thereof;
FIG. 18 is a front view of a fifth image thereof;
FIG. 19 is a front view of a sixth image thereof;
FIG. 20 is a front view of a seventh image thereof;
FIG. 21 is a front view of a eighth image thereof;
FIG. 22 is a front view of a ninth image thereof;
FIG. 23 is a front view of a tenth image thereof;
FIG. 24 is a front view of a eleventh image thereof;
FIG. 25 is a front view of a twelfth image thereof;
FIG. 26 is a front view of a thirteenth image thereof;

(Continued)

FIG. 27 is a front view of a third embodiment of a display screen or portion thereof having a graphical user interface for displaying an animated wait icon showing my new design;

FIG. 28 is a front view of a second image thereof;

FIG. 29 is a front view of a third image thereof;

FIG. 30 is a front view of a fourth image thereof;

FIG. 31 is a front view of a fifth image thereof;

FIG. 32 is a front view of a sixth image thereof;

FIG. 33 is a front view of a seventh image thereof;

FIG. 34 is a front view of a eighth image thereof;

FIG. 35 is a front view of a ninth image thereof;

FIG. 36 is a front view of a tenth image thereof;

FIG. 37 is a front view of a eleventh image thereof;

FIG. 38 is a front view of a twelfth image thereof; and,

FIG. 39 is a front view of a thirteenth image thereof.

The appearance of the animated design transitions sequentially between the images shown in FIGS. 1-13, 13-1, 14-26, 26-14, 27-39, and 39-27.

The broken lines showing a device form no part of the claimed design. The broken lines showing a display screen form no part of the claimed design.
